No. 790,274.

PATENTED MAY 23, 1905.

C. W. BECK.
ACETYLENE GAS GENERATOR.
APPLICATION FILED SEPT. 24, 1900.

UNITED STATES PATENT OFFICE.

CHARLES W. BECK, OF NEW YORK, N. Y., ASSIGNOR, BY MESNE ASSIGNMENTS, TO ELECTROLITE GAS LAMP COMPANY, OF NEW YORK, N. Y.

ACETYLENE-GAS GENERATOR.

SPECIFICATION forming part of Letters Patent No. 790,274, dated May 23, 1905.

Application filed September 24, 1900. Serial No. 31,003.

To all whom it may concern:

Be it known that I, CHARLES W. BECK, of New York, county of New York, and State of New York, have invented certain new and useful Improvements in Acetylene-Generators, of which the following is a specification.

This invention relates to improvements in acetylene-generators, and refers more specifically to a generator of that type wherein the carbid in granulated or pulverulent form is fed to a body of water in graduated quantities automatically controlled by the pressure of gas generated, the particular embodiment of the invention shown herein consisting of a portable table-lamp or lamp for domestic and analogous purposes.

Among the objects of the present invention are to provide improvements in the details of construction and arrangement of the carbid-feeding mechanism; to so construct and arrange the operative parts that the expansible bag which operates the carbid-feeding mechanism may be located at or near the bottom of the generator; to provide an improved safety device whereby access of water to the carbid-chamber is prevented in case the lamp be accidentally overturned; to provide an improved construction in a reducing-valve or regulating device whereby the flow of gas from the generator to the burner is controlled; to provide improved means for locking the carbid-feeding mechanism in closed position, and in general to provide a simplified and improved detail of construction contributing to the economy of manufacture, efficiency of operation, and convenience of manipulation of the lamp.

To the above ends the invention consists in the matters herein described, and more particularly pointed out in the appended claims, and the same will be readily understood from the following description, reference being had to the accompanying drawings, in which—

Figure 1 is an axial vertical sectional view of a lamp forming a preferred embodiment of my invention. Fig. 2 is a fragmentary detail of meeting portions of the font and of the upper member of the generator, showing

more particularly one of the catches whereby said members are detachably united.

In said drawings, 1 designates as a whole the bowl or font portion of the generator, made globular in the present instance and supported upon any suitable hollow base—as, for example, the sheet-metal base, (designated 50 as a whole 2,)—and 3 designates as a whole the upper detachable member of the generator, the interior of the lower portion of which is in open communication with the upper part of the font and forms in conjunction with the latter the generating space or chamber 5, while the upper portion forms the carbid chamber or receptacle 6.

In the preferred embodiment shown herein the font and upper member 3 are detachably 65 united by means of a joint and packing of peculiar construction adapted to form a gas-tight union between said parts, while at the same time capable of being conveniently disconnected and united. To this end the upper edge 7 70 of the lower member is thickened and provided in its upper surface with a circumferential groove 8, adapted to contain a packing-ring 9, while the meeting lower edge of the upper member is provided with a meeting surface 10, adapted to rest upon the packing-ring, and with an external depending flange portion 11, which overlaps the inner side of the packing-ring and serves, in conjunction with the groove 8, to hold the latter accurately 75 in position throughout its entire circumference. As a convenient means of holding the two members together and the packing-ring in compression between the two the lower member is provided with a plurality of up- 80 standing rigid hooks 12, (see detail view, Fig. 2,) while the upper member is provided with correspondingly-located studs 13, adapted for engagement with said hooks, and in order to facilitate the engagement of the studs with 85 the hooks the ends of the latter are inclined upwardly, as indicated at 14, so as to act upon the studs cam fashion to force the upper member downwardly into compressed engagement with the packing-ring as said member 90 is rotated into engagement with the hooks.

The carbid-chamber 6 is separated from the generating-chamber 5 by means of a conical or hopper-shaped partition 15, provided at its apex with a feed-aperture 16, through which 5 works a feed-plunger 17. The feed-plunger comprises a cylindric portion 18, working through a rubber diaphragm or packing-ring 19, mounted on the lower end of the hopper concentric with the feed-aperture therein, and 10 below this cylindric portion a reduced portion 20, terminating in a conical deflector 21. The diaphragm 19 consists of a ring of rubber having its perimeter which bears against the feed-plunger brought to a blunt edge, as indicated clearly in the drawings, and in order 15 that the size of the opening through said diaphragm or ring may be varied or reduced from time to time to compensate for wear and maintaining a substantially gas-tight rubbing 20 contact between said parts said ring is mounted in a cylindric cup-shaped housing 22, the lower end of which is partially closed by an annular cap 23 threaded thereon and adapted to compress the ring within the cup, and 25 thereby reduce its internal diameter.

Describing now the mechanism whereby the feed-plunger is reciprocated to feed the carbid from the hopper to the generating-chamber, 24 designates a cylindric chamber arranged in the lower part of the generator and provided at its upper side, at a point in axial alinement with the plunger, with a tube or upward extension 25, the upper end of which is open and terminates at a point somewhat 30 below the lowermost position reached by the deflector 21 in its normal operation, but which serves as a stop to arrest the downward movement of the feed-plunger when it descends below the normal. Within the chamber 24 35 is arranged an expansible gas-bag 26, preferably made of rubber of suitable size to be capable of being expanded to substantially fill said chamber 24 and having its mouth or inlet fitted and secured around the opening in the upper side of the chamber which communicates with the extension 25 by means of a screw-plug 27, threaded into the lower end of 40 said tube 25 and the head of which is arranged to compress and hold the marginal edge of 45 the mouth of the bag between itself and the upper wall of the chamber.

28 designates a hollow stem or extension connected at its upper end with the lower end of the feed-plunger and extending thence 50 down through the tube 25 into the chamber 24 and through the lower side of the gas-bag. Upon the lower side of the gas-bag is arranged a rigid disk 29, preferably covering the principal area of the lower side of the bag, and 55 with this disk the stem 28 is rigidly united by means of clamping-nuts 30 31, threaded upon said stem respectively inside and outside of the gas-bag, so as to clamp the latter and the disk 29 between them. The lower end of 60 the hollow stem is closed by means of a screw- 65

70 plug 32. Inlet-openings 33 affording communication between the interior of the stem and the gas-bag are provided in said stem adjacent to its lower end, and similar inlet-openings 34 are provided in the upper end of said stem at a point immediately below the deflector 21.

In order to force the feed-plunger upwardly 75 into position to carry its reduced portion 20 into register with the diaphragm 19, and thus permit the carbid to flow from the hopper, a coiled extension-spring 35 is arranged within the tubular extension 25, its upper end being arranged to act upon the under side of the deflector, while its lower end engages the inner 80 end of the plug 27. Preferably, in order to prevent the access of water from the reservoir to the gas-bag in case the lamp be shaken or partially overturned, that portion of the stem which extends through the tubular extension 85 25 is arranged to work through a packing-tube 36, fitting closely upon the stem and having its lower end threaded into the plug 27, so as to hold it in position.

In order to lock the feed-plunger in closed 90 position—*i. e.*, in a position low enough to bring its cylindric portion 18 into register with the diaphragm 19—a vibratory lever 37 is pivoted between its ends in the lower part of the base, as at 38, one end of the lever being arranged to extend out through a suitable vertically-disposed slot 39 in the base, while its opposite end is arranged to extend loosely through a transverse aperture 40 formed through the screw-plug 32, which engages the lower end of the feed-plunger stem. That end of the lever which extends out through the base is suitably shaped to form a handle or thumb-piece 41 whereby the lever may be manipulated, and in order to lock 105 this end of the lever in its uppermost position a catch 42 is pivoted to its lower side, as at 43, provided at one end with a notch 44, adapted to engage the lower end of the slot 39, while its opposite end is suitably shaped to enable it to be manipulated into engagement with the slot when this end of the lever is uplifted. The catch 42 has sufficient frictional 110 engagement with its pivot to hold it in any position of adjustment without the use of a 115 spring or the like, so that when adjusted into the position shown in the drawings it will remain in this position and not interfere with the movement of the lever when oscillated by the alternate inflation and deflation of the gas-bag.

The gas generated in the generating-chamber passes into the carbid-chamber through a tube or inlet-pipe 45, mounted to extend vertically through the hopper-bottom and having its discharge end located near the top wall of the carbid-chamber. In order to prevent the flow of water to the carbid-chamber through the said inlet-pipe in case the lamp be accidentally overturned, I have provided a 125 130

novel safety device (designated as a whole 46) comprising a short length of flexible waterproof tubing (preferably rubber) 47, connected at one end with the lower end of the inlet-pipe 45, so as to communicate with the latter, and provided at its opposite end with a weight 48, having an inlet-aperture 49, through which the gas may enter, said weight serving to normally hold the tube straight and in alinement 5 with the inlet-tube, so as to afford a free passage therethrough, but acting to fall over to one side or the other in case the lamp be overturned, so as to form an abrupt bend in the flexible tube, and thus close the passage therethrough. From the upper part of the carbid-chamber the gas is admitted to a reducing or regulating valve, (designated as a whole 50,) which is also of novel construction and forms one feature of the present invention. As preferably constructed said valve comprises a hollow cylindric valve-body 51, provided at intervals along its cylindric sides with inlet-apertures 52, which are preferably covered by means of a porous wrapping or filter-cloth 53, so as to prevent access of dust or carbid to the chamber while permitting the passage of the gas. The stem of the feed-plunger 17 is prolonged upwardly, so as to enter the lower end of said reducing-valve, and in order to prevent the access of carbid at this point the said stem is arranged to work through a diaphragm-ring 4, constructed and arranged substantially similar to that at the lower end of the carbid-hopper, as shown clearly in the drawings. The upper portion of the valve-chamber is provided with a transverse diaphragm 54, having an aperture or gas-passage 55 formed therein, through which is arranged to work a downwardly-tapering slide or throttle 56, having its lower end connected with the stem of the feed-plunger, so as to reciprocate with the latter.

As a convenient and desirable construction whereby the reducing-valve may be supported in the upper part of the carbid-chamber in such manner as to be readily disconnected and removed therefrom the top wall of said carbid-receptacle is provided with an opening large enough to receive the cylindric body of the valve, and the latter is provided with a reduced threaded nipple 57, over which is arranged to fit a cap 58, having its periphery turned downwardly to rest in contact and form a close joint with the top wall of the generator, as indicated at 59, and upon said nipple is threaded the lower end of the burner 60 in such manner as to clamp the cap 58 between its lower end and the shoulder formed at the junction of the main body of the valve with the nipple, thereby connecting the cap with the valve, supporting the latter within the hopper through the medium of the cap, and uniting the burner-nozzle with the valve by the single threaded connection.

The hopper and font are provided with

suitable filling-apertures 61 and 62, respectively, each closed by suitable screw-plugs, as usual.

In order that the pressure within the generator may never rise to a dangerous point, the generator is desirably provided with a safety-valve, which is conveniently located in the side wall of the generating-chamber at a point immediately below the bottom of the hopper and designated as a whole 62'. This safety-valve may be of any well-known or preferred construction, that shown herein consisting of a cylindric valve-body 63, seated within and extending through the side wall of the generator and having a closed inner end through which is formed a port 64. The outer end of said valve-body is closed by means of a screw-plug 65, through which is arranged to work the stem 67 of a puppet-valve 66, which is held in bearing with the port 64 by means of an expansion-spring 68 in the usual manner. Obviously the tension with which the valve is held against its seat may be regulated by means of the screw-plug 65.

The operation of the apparatus constructed as thus described is probably entirely obvious to those skilled in this art, but may be briefly described, as follows: Assuming that the feeding mechanism is locked against movement in the manner herein described, a suitable quantity of liquid is charged into the font through the filling-aperture thereof and likewise a suitable quantity of granulated or pulverized carbid is charged into the carbid-hopper through its filling-aperture. The lamp may now be brought into operation by simply unlocking the feeding mechanism, whereupon the spring of the feed-plunger will force the latter upwardly, discharging the air which may be in the gas-bag and at the same time carrying the feed-plunger into a position to permit the flow of carbid from the hopper downwardly into the generating-chamber, the pulverulent carbid being deflected by the conical deflector 21, so as to be dispersed over the liquid. The generation of gas from the granulated carbid will be very rapid, and the gas thus generated will pass through the hollow stem downwardly into the expansible bag, inflating the latter and forcing its lower side, and with it the feed-plunger, downwardly until the flow of carbid is arrested by the enlarged portion of the feed-plunger being brought into register with the rubber diaphragm-ring. The gas which is thus generated is also free to escape up through the inlet-tube 45, where it passes over the surface of the body of carbid within the hopper and is thereby dried and thence passes into the lower chamber of the reducing-valve and from the latter up through the valve-controlled port 55 to the burner. Inasmuch as the expansion-spring of the feed-plunger acts constantly to deflate the gas-bag,

the flow of gas will be continuous, notwithstanding the generation has been arrested by the shutting off of the flow of carbid to the generating-chamber, until the gas-bag has been deflated sufficiently to allow the feed-plunger to rise to a point where the feeding of carbid again commences, whereupon a fresh supply of gas will reinflate the gas-bag. The control of the feed is therefore perfectly automatic and determined or controlled absolutely by the consumption of gas at the burner. By reason of the fact that the expansion-spring of the feed-plunger exerts a constantly-increasing tension as the gas-bag becomes inflated more and more the flow of gas to the burner would be correspondingly augmented if means were not provided for regulating and counteracting this increased pressure. By reason of the construction of the reducing-valve, however, the descent of the feed-plunger as the gas-bag is inflated serves to diminish the size of the port through the reducing-valve, and if the slide 56 controlling said port be of properly-tapered form this throttling of said port will practically counterbalance the increased pressure, and therefore render the flow of gas to the burner substantially uniform regardless of the fluctuations in pressure within the generator. The operation of the safety device 46 in preventing the flow of water to the carbid-chamber in case the lamp be accidentally overturned has been clearly described and need not, therefore, be repeated. It may be noted in this connection that should the lamp happen to be overturned but a small quantity of liquid could reach the carbid around the reduced part of the feed-plunger, and this would result in inflating the gas-bag, and thus shutting off the flow of liquid to the carbid, precisely the same as though the lamp were erect, while in the event that sufficient liquid had already reached the carbid to produce an excess of pressure the safety-valve would act to relieve the same. After the lamp has been operated long enough, so that it becomes necessary to remove the residue from the font, the upper member of the generator is disconnected from the font by rotating it sufficiently to disengage its catches, whereupon the font may be emptied out and cleaned in an obvious manner.

I claim as my invention—

1. In an acetylene-generator, the combination of a water-chamber, a carbid-chamber supported above said water-chamber, an intervening space between the surface of the liquid in the water-chamber and the bottom of the carbid-chamber constituting a generating-chamber, a feed-plunger working through the bottom of said carbid-chamber, a chamber located below the liquid within the water-chamber, an extension rising from said lower chamber above the level of the liquid within the water-chamber, an expansible gas-bag within said lower chamber and operative connections

extending from the gas-bag up through the extension and connected with the feed-plunger.

2. In an acetylene-generator, the combination of a water-chamber, a carbid-chamber supported above said water-chamber, an intervening space between the surface of the liquid in the water-chamber and the bottom of the carbid-chamber constituting a generating-chamber, a feed-plunger working through the bottom of said carbid-chamber, a chamber located below the liquid within the water-chamber, an extension rising from said lower chamber above the level of the liquid within the water-chamber, an expansible gas-bag within said lower chamber and operative connections extending from the gas-bag up through the extension and connected with the feed-plunger and a carbid-deflector mounted upon the plunger and overlying the upper end of said extension, whereby the carbid is deflected and prevented from falling within the extension.

3. In an acetylene-generator, the combination of a water-chamber, a carbid-chamber supported above said water-chamber, an intervening space between the surface of the liquid in the water-chamber and the bottom of the carbid-chamber constituting a generating-chamber, a feed-plunger working through the bottom of said carbid-chamber having a reduced portion adapted to permit the flow of carbid through the feed-opening when brought into register with the latter, a lower chamber arranged below the liquid within the water-chamber and provided at its upper side with an extension rising above the normal level of the liquid in the water-chamber, an expansible gas-bag within said lower chamber, a hollow stem connected with the feed-plunger and extending thence down through the extension and connected with the remote side of the gas-bag, gas-ports located in the upper and lower portions of the hollow stem and affording communication between the generating-space and interior of the gas-bag and a spring arranged within said extension and acting on the plunger to press it normally upward into feeding position.

4. In an acetylene-generator, the combination of a water-chamber, a carbid-chamber supported above said water-chamber, an intervening space between the surface of the liquid in the water-chamber and the bottom of the carbid-chamber constituting a generating-chamber, a feed-plunger working through the bottom of said carbid-chamber having a reduced portion adapted to permit the flow of carbid through the feed-opening when brought into register with the latter, a lower chamber arranged below the liquid within the water-chamber and provided at its upper side with an extension rising above the normal level of the liquid in the water-chamber, an expansible gas-bag within said lower chamber, a hollow stem connected with the feed-plunger and extending thence down through the ex-

tension and connected with the remote side of the gas-bag, gas-ports located in the upper and lower portions of the hollow stem and affording communication between the generating-space and interior of the gas-bag, a spring arranged within said extension and acting on the plunger to force the latter normally upward into feeding position, and a packing arranged within said extension fitting the hollow stem and serving in conjunction with the extension to exclude liquid from the gas-bag, substantially as described.

5. In an acetylene-generator, provided with a supporting-base, the combination with a water-chamber, a carbid-inlet above said water-chamber and a feed-plunger working through said inlet, of an extension connected with said feed-plunger and extending down through the water-chamber to the base of the generator and means for locking said plunger against vertical movement, comprising an arm extending from the lower end of said extension out through the side wall of the base and means for locking said arm against movement.

20 6. In an acetylene-generator provided with a supporting-base, the combination with a liquid-font supported upon said base, a carbid-hopper arranged in the upper part of said generator, a generating space or chamber between the hopper and the surface of the liquid within said font, a feed-plunger working through a feed-opening in the bottom of said hopper, an expansible gas-bag arranged within the lower 25 part of the generator below the liquid-chamber, a stem connected with the lower end of the feed-plunger and extending thence downwardly through the liquid-font and through the expansible gas-bag and operatively connected with the lower side of the latter, a spring acting upon said feed-plunger to normally raise the latter and means for locking said feed-plunger against vertical movement, comprising a lever pivotally supported in the lower 40 part of the base below the gas-bag and having one of its ends flexibly connected with the lower end of said stem and its opposite end extended laterally out through the side wall of the base, and a catch for locking said lever 45 against oscillation, substantially as described.

50 7. In an acetylene-generator of the character described, the combination with the vertically-reciprocating feed-plunger stem having a part provided with a transverse aperture, of an oscillatory locking-lever pivotally mounted between its ends and having one end engaging said transverse aperture and its opposite end constructed to form a handle and a catch connected with the handle end of said 55 lever and adapted to engage a fixed part of the generator to lock the lever against movement, substantially as described.

60 8. In combination with a portable generator, having two chambers and an inlet affording communication between said chambers,

means for automatically shutting off said communication when the generator is moved out of vertical, comprising a length of flexible tubing connected to and communicating with said inlet and a weight suspended thereby, whereby the tube is held straight and open when the generator is upright and is bent upon itself to close the passage therethrough when the generator is tilted out of vertical.

9. In combination with an acetylene-generator, having an upper carbid-hopper, a subjacent water-chamber and an intervening gas-space, an inlet-tube extending through the bottom of said carbid-hopper, a length of flexible tubing connected with said inlet-tube and a perforated weight connected with the lower end of said tubing, substantially as described.

10. In an acetylene-generator, the combination of a water-chamber, a carbid-chamber above said water-chamber, an intervening space between the surface of the liquid in the water-chamber and the bottom of the carbid-chamber constituting a generating-chamber, a feed-plunger working through the bottom of said carbid-chamber, a chamber located below the liquid within the water-chamber, a tubular extension rising from said lower chamber above the level of the liquid within the water-chamber, an expansible gas-bag within said lower chamber, operative connections extending from the gas-bag up through the extension and connected with the feed-plunger and a carbid-deflector mounted upon the plunger and overlying the upper end of said extension, the upper end of said extension being so located as to form a stop serving to arrest the expansion of the gas-bag when it approaches complete inflation, substantially as described.

11. In an acetylene-generator, the combination with a vertically-reciprocating feed-plunger adapted to control the feed of pulverulent carbid, of means for locking said plunger against movement in position to close the feed-passage, comprising a pivoted manipulative lever flexibly connected with said feed-plunger and normally moving with the latter, and means for locking said lever against movement.

12. In a gas-lamp, tanks or chambers for separately holding gas-generating elements, a passage from one to another, a valve between them, a collapsible gas-chamber in communication with the gas-space in said tanks, said valve being connected with said collapsible gas-chamber in such manner that when the latter is extended the passage from one tank to the other is closed and means for manually expanding said collapsible gas-chamber, said means comprising a lever in engagement with said collapsible gas-chamber, said lever adapted to be moved thereby and a device for coacting with said lever to check its movement.

13. In a gas-generator, the combination of chambers for separately holding the gas-generating elements, a passage from one of said

chambers to the other through which one generating element is fed to the other, a feed-valve controlling said passage, an expansible and collapsible gas-holder, operative connections between said holder and the feed-valve, and a reducing-valve connected to the feed-valve and operated by the movement thereof.

14. In a gas-generator, the combination of chambers for separately holding the gas-generating elements, a passage from one of said chambers to the other through which one generating element is fed to the other, a feed-valve controlling said passage, an expansible and collapsible gas-holder, operative connections between said holder and the feed-valve, a gas-outlet from the generator, a valve for said outlet, and means for simultaneously operating the feed-valve and the outlet-valve.

15. In a gas generator or lamp the combination, of chambers for separately holding gas-generating elements, a passage from one of said chambers to the other, a valve controlling said passage, an expansible and collapsible gas-holder in communication with the gas-space of said chambers, operative connections

between the valve and said expansible and collapsible gas-holder, and a lever for manually expanding the gas-holder, and for locking it in its expanded position to stop the feed.

16. In a gas generator or lamp, tanks or chambers for separately holding gas-generating elements, a passage from one to another, a valve between them, an expansible and collapsible gas-chamber in communication with the gas-space in said tanks said valve being connected with said expansible and collapsible gas-chamber in such manner that when the latter is expanded the passage from the one said tank to the other is closed, a spring arranged to act against the gas-pressure in the collapsible gas-chamber, and mechanism for preventing the said spring collapsing the gas-chamber, and thereby stopping the feed, said means comprising a lever in engagement with the gas-chamber and means for locking said lever against movement.

CHARLES W. BECK.
